UNITED STATES PATENT OFFICE.

CHARLES D. McDONALD AND CHARLES E. ENNES, OF CHICAGO, ILLINOIS, ASSIGNEES
TO THE McDONALD MACHINE CO., OF CHICAGO, ILLINOIS, A CORPORATION OF
ILLINOIS.

MACHINE FOR PLACING PAPER RINGS IN CAN-HEADS.

1,194,759.

Specification of Letters Patent. Patented Aug. 15, 1916.

Application filed September 7, 1915. Serial No. 49,233.

To all whom it may concern:

Be it known that we, CHARLES D. McDONALD and CHARLES E. ENNES, citizens of the United States, residing at Chicago, in the county of Cook and State of Illinois, have invented certain new and useful Improvements in Machines for Placing Paper Rings in Can-Heads, of which the following is a specification.

10 The present invention relates to a machine for cutting and positioning a liner in the form of paper ring within a groove or seat in a can head.

15 The objects of the invention are to position a circular paper disk within a seat in a carrier to move the carrier into position, where the disk carried thereby will aline with a cutting die which is operated to cut the center out of said disk and form a ring; 20 to carry said ring into position to aline with a seat in a second carrier, in which has been positioned a can head; to operate a positioning die for forcing the ring into the seat in the alined can head; to then spin or turn 25 over the edge of the can head, thereby firmly securing the ring in position; and to then stack the completed can head with the liner therein within a suitable receptacle. All of the above is carried out automatically, 30 whereby the operator has no duty to perform save replenishing from time to time the supply of disks and can heads, and carry away from time to time the can heads with the liners therein.

35 The invention further consists in the features of construction and combination of parts hereinafter described and claimed.

In the drawings: Figure 1 is a front view of the machine of the present invention; Fig. 40 2 is an end view of said machine; Fig. 3 is a plan view; Fig. 4 is a section on line 4—4 of Fig. 3, looking in the direction of the arrows; Fig. 5 is a section on line 5—5 of Fig. 1, looking in the direction of the arrows; 45 Fig. 6 is a section on line 6—6 of Fig. 1, looking in the direction of the arrows, with the transmission mechanism only; Fig. 7 is a view of the paper disk; Fig. 8 is a view of the ring liner formed from said disk; 50 Fig. 9 is a section showing the ring liner in place; and Fig. 10 is a section showing the

ring liner in position within the can head and the edges of the can head turned over to retain the ring in place.

In the art to which the present invention 55 relates, the feature to be accomplished is the positioning of a ring liner within a can head which acts as a seal when the head is placed upon a can, thus preventing a leakage and consequent spoiling of the contents. In the 60 present invention, this assemblage is brought about by automatic means, the only manual operation being the placing of the can heads and paper disks within suitable magazines, and the stacking or piling of the can heads 65 with the liners therein within a suitable receptacle.

The mechanism is mounted upon a frame consisting of a base 11, supporting legs or standards 12, and a top or table 13. This 70 supporting frame can be of any suitable construction. The machine embodies three magazines or containers; the first, designated generally by the numeral 14, being for the paper disks; the second, designated 75 generally by the numeral 15, being for the can heads; and the third, designated generally by the numeral 16, being for the purpose of receiving the can heads after the rings have been positioned therein. 80

The first step in the operation of the machine is the extracting of the paper disks from the magazine or receptacle 14. This magazine, as shown, consists of a tubular member 17 held in position by a suitable 85 bracket or support 18, the magazine, as shown, having its lower end spaced away from the table 13. In order to prevent more than one of the disks which are designated by the numeral 19 from being extracted at 90 a time, pivoted fingers or keepers 20 are provided, which underlie the lowermost of the pile of disks within the receptacle. The extraction of the disks is brought about by means of a suction head 21 which is attached 95 to a tubular member 22, the interior of which is in communication with a suction supply pipe 23 extending from any suitable source of suction.

The tubular member 22 is attached to a 100 slotted plate or straddler 24 which carries a roller 25, resting against the periphery

of a cam 26. This cam is located on a main drive shaft 27 operated from any suitable source of power. A spring 28 is employed which holds the tubular member 22 and suction head 21 normally upward. It is obvious that, as the cam 26 revolves, it will produce a raising and lowering of the suction head by reason of its configuration and the coöperation of the spring 28. Each time the suction head engages with the lowermost of the disks 14 within the receptacle 17, it will adhere thereto, and the downward movement of the suction head will extract the disk from the pile within the receptacle and bring it into a seat 29 in a revoluble disk or carrier 30. The seats 29 are composed of companion members 30^a, each formed of companion semi-cylindrical portions 31, to each of which is attached a plate 32. Each of these plates is slidable within a way 33 and is held normally projected forward by a spring 34, and each of the plates has an upwardly extending protuberance or shoulder 35^a, the function of which will hereinafter appear. The inner diameter of the seat 29 is somewhat smaller than the outer diameter of the disk, whereby, when the disk is pulled by the suction cup down into the seat, the hold of the suction cup will be broken by the disk engaging with the portions 31 of the seat, and the disk will thus be deposited in the seat. After the disk has been thus deposited, the next operation is a movement of the carrier 30 a quarter revolution, and at the same time this carrier is moved a can head carrier 36 is also moved a similar distance. The mechanism for causing this advancement is shown better in Figs. 3, 4, and 6, and comprises a Geneva wheel 37, operated by an arm 38, which is carried by a disk 39. This disk is rotated by the movements of a shaft 40, and the shaft in turn has secured at its lower end a beveled gear 41 meshing with a beveled gear 42 mounted upon the main drive shaft 27. The Geneva wheel is attached to a stub shaft 45, to which is secured at one end a gear 46, and to the other end of which is secured the can top carrier 36. The gear 46 meshes with a pinion 47 which meshes with a gear 48 that is secured to a stub shaft 49, which shaft carries and revolves the disk carrier 30. From the foregoing, it will be apparent that each of the carriers 30 and 36 is revolved in a step by step movement, but in opposite directions, as indicated by the arrows in Fig. 3. The first movement of the carrier 30 brings the disk of paper carried thereby beneath a ring cutting male die member 50 with which is associated a spring backed stripper ring 50^a. The members 30^a of the seats 29 act as coöperating female dies for this male die 50. This die member is carried by an elongated travelling head 51 which is

slidable up and down within suitable ways 52. As the die 50 descends, it cuts the interior from the disk of paper 19, thereby producing the ring 52^a shown in Fig. 8. The center portion of this ring drops into a chute 52^b and is thus discharged, and from it a second ring, for use with a smaller sized can head, can be made.

The means for moving the slidable head up and down consists of a member 53, to each end of which is attached a rod 54 connected with the head 51, and depending from the member 53 is a piece 55 carrying a roller 56 traveling within the groove 57 of a cam 58 mounted upon the shaft 27. As will be apparent from Fig. 5, as this can revolves, it will force the member 53 up and down, and through the instrumentalities of the connection 54 between the member 53 and the head 51, said head will be reciprocated. The head always moves in a downward direction during the period of rest of the carriers 30 and 36, so that the work is always in position beneath the various members carried by the head when the head is moved downward. After this ring 52^a has been cut in the manner above specified, it is left within the seat, and the carrier 30 is advanced a second step. This brings the seat, in which the ring has been placed, beneath a positioning die 59 which is also mounted upon the slidable head 51. This positioning die descends, and a sloping surface 60 thereon engages with the protuberances 35^a on the plates 32, forcing these plates back, and allowing the ring 52 to drop out of its carrier and into a groove 61 of a can head 62, which can head has been advanced into position beneath the ring by means of the movement of the can head carrier 36. Suitable seats 63 are formed in said carrier to support said heads. The continued downward movement of the positioning die forces the ring into the groove 61, and from that point on, the can head and ring are carried by the same carrier until finally discharged. The next operation of the machine is to bring the cap with the ring liner in place therein around to a position where a mechanism acts to bend or crimp the flange of the can head to turn over the same. This takes place at the point indicated by the numeral 64, as shown in Fig. 3. When in this position, the cap is held between spinning dies, comprising an upper die member 65 and a lower die member 66. The die member 65 is carried by the head 51 and revolves within a ball bearing, as is shown in Fig. 5. The lower die member comprises a member 66 mounted upon a stem 67, which stem is slidable up and down and revoluble. It is revolved by means of a stub shaft 74, to which is joined a beveled pinion 69 driven by a beveled gear 88 on a stub shaft 43 connected to the main

drive shaft by a gear connection 44. The stub shaft 74 has a keyed telescopic connection with the stem 67, so that relative longitudinal sliding movement is permitted between the stem and stub shaft, but they are revolved in unison.

The up and down motion to the stem 67 is imparted by a cam 70, as shown in Figs. 1 and 5, which cam is also mounted upon the shaft 43. This cam engages with the roller 71 attached to a fork-like member 72 which engages with an abutment 73, and this abutment in turn engages with the stem 67. When the die 65 engages one face of the can head and the die 66 engages the opposite face, the head is clamped between the two, and the rotative movement of the head 66 spins the can head thus clamped. Prior to this spinning movement, a turning or crimping roller 75 has been brought into engagement with the flange 76 of the can head, and acts to turn this flange over to form the bend, or crimp 77, as shown in Fig. 10. The roller 75 is mounted on a slideable member 78 traveling in ways 79, and is reciprocated back and forth by means of a rocking lever 80 connected to a link 81, and in turn connected to a lug 82 extending from the plate 78. This rocking lever 80 is mounted on a rock shaft 83 suspended within a sleeve 84 extending from the bracket 85, as shown in Fig. 1. To the opposite end of the rock shaft from that which is connected to the lever 80 is a link or arm 86, carrying on its end a roller 87 which rests against the periphery of a can 88 mounted on the shaft 43. Connected to the arm or link 86 is a spring 89 to normally hold it inwardly. It is thought that the operation of this portion 40 of the device will be apparent from Figs. 1, 2, and 5. After the flange of the can head has been thus turned or crimped, the liner is completely inserted within the head groove, and the next operation is to discharge the can head with the liner therein from the machine. To accomplish this, I provide an opening 90 in the top of the table 13, and when the can tops carried by the carrier 36 come opposite this opening, 45 the can top thus brought into position tilts downward by the action of gravity, and is guided by the plate 91 onto the surface of a table 92. Working above the surface of this table is a finger 93 carried by a sliding member 94 actuated by a crank 95 connected to the disk 39. This finger pushes the can top to a position beneath the magazine 16. This magazine consists of four rods 96 suitably joined together, and at the lower end 50 of these rods are swinging fingers 97, which are adapted to open outwardly under the influence of a pressure from beneath. A striker 98 is located beneath this receptacle, and is carried by a rod 99 which has connected thereto a slotted straddler 100. This

straddler carries a roller 101 which rests against the periphery of a cam 102, which cam is mounted on the shaft 27. A spring 105 is employed which tends to hold the striker normally upward. At each upward movement of this striker, it forces a can head upward and past the fingers 97, depositing it within the magazine 16, as shown in Fig. 4, and when a sufficient pile of can heads has thus been created, they can be removed as desired.

To feed the can heads from the magazine 15 into the can head carrier, I employ a plate 106 having a V-shaped end 107, which plate travels beneath the lower end of the magazine, as shown in Figs. 3 and 5. This plate is reciprocated back and forth by means of a link 108 connected to a lug 109 depending from said plate. Said link is connected to an arm 110, on which is a roller 111 operating in a cam groove 112 in a disk 113, as shown in Fig. 5. This cam disk is mounted on a shaft 103 which is connected to the shaft 43 by a gear connection 104. The plate 106 slides within suitable guide- 90 ways 114.

The operation briefly is as follows: The can heads are placed within the magazine 15, and paper disks are placed within the magazine 14. The machine is then started, 95 and the sucker head 21 rises and extracts the lowermost of the disks 19 from the pile of disks within the magazine 14. This disk is drawn down by the action of the sucker head and placed within the seat 29 of the 100 disk carrying member 30. The disk carrier is then revolved one step, and the cutting die 50 then operates to cut the interior from said disk, producing the ring 52. The next step of the carrier 30 brings the ring into 105 alignment with the groove 61 of a can head 62, which has been advanced by the carrier 36 into position beneath the seat 29 of the carrier 30 in which the ring is located. The assembling die 59 then acts to first spread 110 apart the members 31 by engagement with the lugs 35^a, thus releasing the ring 52^a and allowing it to drop into the groove 61 of the can head member 62 lying therebeneath. The subsequent movement of the assembling 115 die fully inserts the ring into said groove, as shown in Fig. 9. The next operation of the machine brings the seat 63 of the carrier 36 which contains the can head, having the ring therein, into position opposite the roller 120 75. This roller is then moved into position by movement of the slide 78 to engage with the flange 76 of the can head. The can head is revolved by the combined action of the spinning dies 65 and 66, and the flange of the 125 can head is turned over to form the crimp 77, as shown in Fig. 10. The next operation brings the seat of the carrier 36 which contains the can head with the turned-over flange into alignment with the opening 90, 130

and the head falls upon the guide 91, and is directed thereby downwardly and onto the table 92 where the finger 93 engages it, and 5 16. Then the plunger 98 acts to force the completed can head through the fingers 97 and into the interior of the magazine, from whence it is ultimately removed. At the same time that the sucker head 21 acts to 10 extract a disk from the magazine, the plate 106 acts to extract a can head 62 from the magazine 15, and position it within the carrier 36.

There are two general movements of the 15 parts of the machine, which movements occur intermittently; the first is the removal of a disk from the magazine 14, a can head from the magazine 15, the placing of a can head with the liner therein in the magazine, 20 16, the downward movement of the head 51, and subsequent actions of the cutting die 50, the assembling die 59, the spinning dies 65 and 66, and the inward movement of the roller 75—these all take place at practically 25 the same time. The second movement is the revolving movement of the carriers 30 and 36 which is intermittent as respects the operation of the other portions of the machine. Thus, there are two sets of movements, one 30 alternating with the other throughout the operation of the machine.

We claim:

1. In a machine of the class described, the combination of a frame, a head slidable 35 on the frame, a cutting die, an assembling die, and a spinning die carried by said head, means for reciprocating said head, means for feeding a paper disk into position beneath the cutting die to have the cutting 40 die act to form a ring therefrom, means for feeding a can top into alined position with the paper ring and beneath the assembling die to allow said die to act to place said ring within the top, said can 45 top feeding means also acting to move said assembled ring and top beneath the spinning die to allow said die to engage one face thereof, a secondary spinning die for engaging the opposite face of the can top, means for 50 rotating one of the spinning dies to turn the can top, and means for crimping the flange of the can top during the turning operation to bend the flange over the paper ring, substantially as described.

55 2. In a machine of the class described, the combination of a frame, a head slidable on the frame, a cutting die, an assembling die, and a spinning die carried by said head, means for reciprocating said head, means 60 for feeding a paper disk into position beneath the cutting die to have the cutting die act to form a ring therefrom, means for feeding a can top into alined position with the paper ring and beneath the assembling 65 die to allow said die to act to place said

ring within the top, said can top feeding means also acting to move said assembled ring and top beneath the spinning die to allow said die to engage one face thereof, a secondary spinning die for engaging the opposite face of the can top, means for rotating one of the spinning dies to turn the can top, means for crimping the flange of the can top during the turning operation to bend the flange over the paper ring, and 75 means for discharging the assembled can top and ring from the machine, substantially as described.

3. In a machine of the class described, the combination of a magazine for paper disks, 80 a magazine for can tops, means for simultaneously feeding a disk from its magazine and a can top from its magazine, a carrier for said disks, a carrier for said can tops, a cutting die, means for moving the disks 85 into position to be acted upon by the cutting die to form a ring therefrom, an assembling die, and means for actuating said assembling die when a can top and a ring are alined one above the other, whereby the ring is 90 placed within the can top, substantially as described.

4. In a machine of the class described, the combination of a ring carrier, a seat formed of movable sections in said ring carrier adapted to receive said ring, a can top carrier, means for shifting the sections of said seat in said ring carrier to discharge the ring therefrom when a can top is alined with said ring, and an assembling die operatively 100 connected for forcing said ring into said can top after said discharge, substantially as described.

5. In a machine of the class described, the combination of an intermittently revoluble 105 ring carrier, an intermittently revoluble can top carrier, means for revolving said carrier in unison and with an intermittent motion, means for selecting paper disks and placing them on the ring carrier, means for feeding the can tops into position on the can top carrier, a ring forming die, an assembling die, and crimping means acting successively to form a paper ring, place the same within a can top, and to crimp the 110 edge of the can top to turn it over the ring, a magazine for the assembled can tops and rings, means for discharging the can tops from the machine, means for stacking the assembled can tops and rings within said 115 magazine, and said disk feeding mechanism and can top feeding mechanism, cutting mechanism and assembling die mechanism, crimping mechanism, and stacking mechanism all acting in unison and with an intermittent movement and during the periods of rest of the movement of the carriers, substantially as described.

6. In a machine of the class described, the combination of a ring carrier, a seat formed 120

of movable sections in said ring carrier, adapted to receive said ring, a can top carrier, an assembling die, means carried by the assembling die for spreading the sections of said seat apart to allow the ring to fall from the carrier and into the groove of an alined can top, and said assembled die on further movement forcing said discharged

ring firmly into the groove of said alined can top, substantially as described.
